UNITED STATES PATENT OFFICE

2,668,640

AIR ENTRAINMENT TYPE POPCORN DISPENSER

Willis E. Clark and John E. Beall,
Los Angeles, Calif.

Application March 4, 1950, Serial No. 147,672

7 Claims. (Cl. 222—156)

1

This invention relates to dispensing equipment particularly adapted for the dispensing of popcorn from a supply of corn within a storage chamber into individual containers at a delivery location.

The dispensing equipment shown in the present application is substantially the same as that disclosed in our copending application Serial Number 147,671. In that application, we have specifically claimed certain mechanism employed in the dispenser for successively feeding individual containers to a delivery location, together with a number of timing and automatic control features related to this container feeding apparatus. The present application, on the other hand, is directed to such features as the manner of accommodation of the various dispenser parts within a housing to attain maximum effectiveness of operation combined with simplicity of construction, while at the same time affording ready access to the interior of the apparatus for filling and servicing.

As will appear, the above results are attained in part by providing a door at the front of the dispenser housing having a central opening affording access to an inner delivery location and carrying on its rear side certain parts movable, upon closing of the door, into interfitting operative relation with various parts carried by the main section of the housing. In this connection, we prefer to mount to the door a popcorn collection chamber into which corn is transferred from a storage chamber within the housing, and from which the corn is then dispensed to the delivery location. This collection chamber may be movable, upon closing the door, to a position overlying a container holder, preferably carried by the main section of the housing, and into which individual boxes or the like may be successively fed from a supply of containers. Particularly contemplated also is the mounting of a collection chamber on the door in such position as to move, upon closing the door, into a predetermined overflow relation with the storage chamber, in which relation any excess corn transferred to the collection chamber overflows into the storage chamber.

In certain respects, the apparatus of the present invention is an improvement on the popcorn dispensing device shown in application Ser. No. 46,597, filed August 28, 1948 by Earnest E. Martin. Specifically, in the Martin application, corn is transferred between a storage chamber and a collection chamber by entrainment in a rapidly moving stream of air, and is carried during such transfer past a transparent

2

viewing wall or dome, to create an eye-catching visual effect upon each operation of the apparatus. An object of the present invention is to provide a dispenser having such an upper viewing wall or dome and yet which is so designed as to facilitate filling of the inner storage chamber beneath the dome. This is achieved by mounting the dome to an upper housing cover adapted for movement from its normal closed condition to an open condition in which the storage chamber is readily accessible for filling.

Further features of the invention involve improved methods of baffling the air entrained corn to direct it most easily and yet positively along the inside of the transparent wall or dome. In this connection, we attain a most attractive visual effect, while also simplifying the dispenser construction and facilitating access to the storage chamber, by discharging the corn openly against an angular baffle element positioned at one end of the viewing wall, this baffle acting to direct the corn along the inside of the wall and toward the collection chamber. In the preferred form of the invention, the baffle is positioned at the rear of a forwardly elongated viewing dome and acts to direct the corn along the inside of the dome and into a forward collection chamber.

The above and other features and objects of the present invention will be better understood from the following detailed description of the typical embodiment illustrated in the accompanying drawings, in which:

Fig. 1 is a front view of a preferred form of automatic popcorn dispenser, with the front door partially broken away to reveal the inner box ejecting apparatus;

Fig. 2 is a transverse vertical section through the dispenser taken on line 2—2 of Fig. 1;

Fig. 3 is a vertical section looking forwardly along line 3—3 of Fig. 2 and showing only those parts of the dispenser that are carried by the housing door;

Fig. 4 is a fragmentary horizontal section taken on line 4—4 of Fig. 3 and showing the popcorn dispensing valve; and

Fig. 5 is a fragmentary vertical section taken on line 5—5 of Fig. 2.

Referring first to Figs. 1 and 2, the illustrated dispensing apparatus is contained within a housing including a stationary main section 10, a door 11 closing the front side of the main section and having a centrally positioned delivery opening 12, and an upper hinged cover 13. The dispensing equipment within the housing includes a rear vertically extending storage chamber 14

for receiving popped corn to be dispensed, a blower 15 for creating an upward flow of air within the storage chamber to entrain and carry corn upwardly and then forwardly along the inside of the cover dome, a collection or measuring chamber 16 carried by the door for receiving the transferred corn, a box holder 17 carried by the main portion of the housing and adapted to hold a single box into which corn is dispensed from the measuring chamber, and box ejecting apparatus 18 for feeding a single box into the box holder upon each operation of the machine.

The main or stationary section of the housing 10 includes a lower rectangular portion 19 carried on legs 20, and an upper vertically extending portion 21. Upper portion 21 of the stationary section of the housing is of a horizontal section corresponding to lower portion 19, except at the front of the housing where the upper portion 21 terminates at a forward wall 22 inwardly recessed for reception of the door 11. Wall 22 has a lower opening 23 affording access to the lower interior of housing portion 21 when the door is in its open condition.

Along most of the vertical extent, storage chamber 14 is rectangular and of horizontal section only slightly less than the stationary section of the housing. At its lower end, chamber 14 has converging side and forward walls 24 leading to a restricted lower air inlet 25 containing an air passing screen 26. Heaters 27 may extend along the converging lower walls of the storage chamber to maintain the corn within the chamber at a proper temperature. Blower 15, driven by motor 28, is contained at the bottom of housing portion 21, and creates a flow of air directed upwardly by an angular discharge line 29 into the lower end of the storage chamber.

The flow of air from blower 15 is conducted upwardly through the corn in the storage chamber by a vertically extending tube 30 mounted to the rear wall of the storage chamber by a pair of straps 31. The lower end of this tube is spaced from the converging storage chamber walls so that corn from the storage chamber may pass downwardly about the end of the tube to be entrained by the upward blast of air from the blower.

Cover 13 is mounted to the stationary section of the housing by rear hinges 291 for upward swinging movement between the illustrated closed condition and an open condition in which the storage chamber is accessible for the addition of corn. Along its transverse center, cover 13 carries a forwardly elongated transparent dome 32 through which the transfer of corn by air entrainment may be viewed upon each operation of the machine. At the rear of the dome, the housing cover carries a corn deflecting baffle 33 curving forwardly to direct the upwardly moving corn from tube 30 along the inside of dome 32. Above its forwardly curving portion, deflecting plate 33 has a rearwardly inclined portion 34 which prevents the trapping of corn above the deflecting plate. The forward portion of dome 32 curves downwardly at 35, to direct the stream of forwardly moving corn downwardly into collection chamber 16 from which a measured quantity of the corn is then dispensed. At opposite sides of dome 32, the cover forms a pair of transparent windows 132 behind which corn may be placed for display.

Vertically extending measuring chamber 16, which may be square in section and formed of sheet metal as shown, is carried by door 11 at

its rear side above box holder 17. The measuring chamber is of a size to contain exactly one box full of corn, and carries an inclined plate 36 about its upper open end along which excess corn overflows downwardly from the measuring chamber into the storage chamber. The dispensing of the measured quantity of corn from chamber 16 is controlled by a sliding valve or plate 37 at the lower end of the measuring chamber. As seen best in Figs. 2 and 4, this plate is slidably retained at its opposite sides by a pair of spaced guides 38 and has a dispensing opening 39A movable into and out of registry with the bottom open end of the measuring chamber. Actuation of this valve is controlled by a solenoid 39 mounted to the inner side of the housing door and connected to the valve plate by a lever arm 40 fulcrumed at 41.

Corn dispensed from measuring chamber 16 is received by a box automatically ejected into the holder or cage 17 carried by forward wall 22 of the main portion of the housing. To the left of holder 17, the main portion of the housing carries the box supply holding and ejecting apparatus 18 which has been described specifically and claimed in our copending application Serial No. 147,671. For present purposes, this apparatus may be briefly described as comprising a pair of spaced vertically extending guides 42 for receiving and guiding a vertically movable elevator 43 carrying a stack of nested boxes 44. Vertical movement of the elevator to successively feed the individual boxes to an upper position for ejection is effected by advancement of a pair of chains 45 at the front and rear of the elevator guides to which the elevator is connected by hooks 46. One of the elevator guides carries a vertically movable claw unit 47 which acts upon each operation to move the top box from the nested stack upwardly from the stack and to then release the box for lateral ejection into holder 17 by a pair of leaf springs 48. Stop 49 engages the second box in the stack during the ejection of the top box to prevent the feeding of more than one box at a time to the delivery location and holder 17.

At opposite sides of holder 17, door 11 carries a pair of rearwardly extending side walls 50 engageable in the closed condition of the door with forward wall 22 of the main section of the housing to form with that forward wall a substantially closed delivery recess behind delivery opening 12 in the door. Wire grill members 51 extend between the lower portions of these side walls 50 and permit downward passage of any spilled corn through chute 52 carried by walls 50 and into waste container 53 removably carried by the door.

Delivery opening 12 in the forward housing door 11 is normally closed by a smaller transparent door 54 suitably guided for downward sliding movement between its closed condition of Fig. 2 and an open condition in which an operator may remove a filled box of corn from holder 17. At its lower end, transparent door 54 carries a depending bracket 55 which is connected with a cord 56 extending upwardly about pulley 57 and then downwardly to carry cylindrical actuating weight 58. Weight 58 is movable vertically in cylinder 59, which has an air discharge opening 60 in its lower end permitting restricted air escape from beneath the weight. As will be understood, weight 58 normally tends to move downwardly to its Fig. 2 position to automatically close door 54, but permits manual opening of the door by outwardly projecting handle 61. After the door has been opened it is automatically but rela-

tively slowly closed, as permitted by the escape of air from beneath weight 58 through opening 60.

To the right of access opening 12, housing door 11 carries at its rear side a coin control device 62, into which a coin may be inserted at 63 to commence the operation of the apparatus. The coin control device may of course have the usual coin return lever 64 and opening 65. Insertion of a coin at 63 actuates microswitch 66 which energizes a timing apparatus 67 in the lower end of the housing to start the sequence of operations later to be described.

In preparing the dispenser for use, a supply of corn is filled into storage chamber 14 about tube 30, and a stack of nested boxes is placed on elevator 43 of the box ejecting apparatus. The dispenser is then connected to a suitable power source, typically an ordinary 110 volt A. C. supply. Upon each operation, insertion of a coin at 63 momentarily closes microswitch 66 to energize timing apparatus 67. This apparatus first energizes blower 28 and the box ejecting apparatus. Blower 28 immediately creates an upward flow of air within the housing through tube 30 to entrain popped corn from the lower end of the storage chamber and carry it upwardly within tube 30 to discharge openly against baffle 33. This baffle directs the upward stream of corn forwardly along the inside of transparent dome 32 within full view of the operator at the outside of the machine. The corn is then directed downwardly by the forward curved portion 35 of the dome into measuring chamber 16, which retains only enough corn to fill a single box and overflows any corn in excess of that quantity downwardly into storage chamber 14. While the corn is being transferred in this manner, a box is fed by the box ejecting mechanism into holder 17 beneath the measuring chamber.

After a box has been fed into the box holder and a measured quantity of corn has been transferred into measuring chamber 16, the timer automatically deenergizes the blower and box ejecting mechanism and energizes solenoid 39 which acts through lever 40 to open dispensing valve 37 and permit the corn within measuring chamber 16 to fall into the box at the delivery location. The operator may then open transparent door 54 to remove the filled box of corn.

We claim:

1. A popcorn dispenser comprising a housing, a storage chamber within the housing for containing popped corn to be dispensed, an overflow collection chamber in the housing having an open upper end and adapted to receive a predetermined quantity of corn and to overflow downwardly any corn received in excess of said quantity, means for creating a flow of air in the housing acting to transfer corn from said storage chamber into said collection chamber, means forming an upwardly facing surface extending about the open upper end of said collection chamber at a location to be engaged by the corn overflowing from said collection chamber and inclined in a direction to deflect the overflow corn toward a location offset to the side of said collection chamber for return to the storage chamber, and means for dispensing the corn from said collection chamber.

2. A popcorn dispenser comprising a housing, 70 a storage chamber within the housing for containing popped corn to be dispensed, an overflow collection chamber in the housing having an open upper end and adapted to receive a predetermined quantity of corn and to overflow down-

wardly any corn received in excess of said quantity, means for creating a flow of air in the housing acting to transfer corn from said storage chamber into said collection chamber, means 5 forming an upwardly facing surface extending about the open upper end of said collection chamber at a location to be engaged by the corn overflowing from said collection chamber and inclined in a direction to deflect the overflow corn 10 into the storage chamber, and means for dispensing the corn from said collection chamber.

3. A popcorn dispenser comprising a housing including a lower portion and a top cover section having a transparent wall and being movable between open and closed conditions, a storage chamber in the housing for containing popped corn to be dispensed, an overflow collection chamber within the housing adapted to contain a predetermined quantity of corn and opening into an upper portion of the storage chamber to overflow downwardly thereinto any corn received in excess of said quantity, means for creating a flow of air upwardly within the 20 housing, means for entraining corn from the storage chamber in said upward flow of air and discharging it upwardly and openly toward the top wall, said last mentioned means including a tube extending vertically within the storage 25 chamber for passing the air and corn upwardly and having an upwardly opening upper discharge end, baffle means formed separately from said tube positioned in the path of the upwardly moving corn and directing it generally horizontally 30 along the inside of the transparent wall within sight from outside of the housing and toward the collection chamber, and means for dispensing the transferred corn from the collection 35 chamber.

4. A popcorn dispenser comprising a housing having a top wall with a transparent portion, a storage chamber in the housing for containing popped corn to be dispensed, an overflow collection chamber adapted to contain a predetermined quantity of corn and to overflow downwardly any corn received in excess of said quantity, means for creating a flow of air upwardly in the housing, means for entraining corn from the storage chamber in said flow of air and discharging it upwardly and openly toward the top wall, said last mentioned means including a tube extending vertically within the storage chamber for passing the air and corn upwardly and having an upwardly opening upper discharge end, baffle means formed separately from said tube for directing said entrained corn along the inside of said transparent portion of the top wall within sight from outside of the housing and then into the collection chamber, and means for dispensing the corn from the collection chamber.

5. A popcorn dispenser comprising a housing having a top wall with a transparent portion, a storage chamber in the housing for containing popped corn to be dispensed, an overflow collection chamber adapted to contain a predetermined quantity of corn and opening into an upper portion of the storage chamber to overflow downwardly thereinto any corn received in excess of said quantity, means for creating a flow of air upwardly in the housing, means for entraining corn from the storage chamber in said flow of air and discharging it upwardly and openly toward said top wall, said last mentioned means comprising a tube extending vertically

within the storage chamber for passing the air and corn upwardly and having an upwardly opening upper discharge end, a baffle formed separately from said tube positioned in the upward path of the corn thus entrained and acting to direct it generally horizontally along the inside of the transparent wall within sight from outside of the housing and toward the collection chamber; and means for dispensing the corn from the collection chamber.

6. A popcorn dispenser comprising a housing having a top wall with a transparent portion, a storage chamber in the housing for containing popped corn to be dispensed, an overflow collection chamber adapted to contain a predetermined quantity of corn and to overflow downwardly any corn received in excess of said quantity, means for creating a flow of air upwardly in the housing, means for entraining corn from the storage chamber in said flow of air and discharging it upwardly and openly toward the top wall, said last mentioned means including a tube extending vertically within the storage chamber for passing the air and corn upwardly and having an upwardly opening upper discharge end, a baffle formed separately from said tube positioned in the upward path of the corn thus entrained and acting to direct it generally horizontally along the inside of the transparent portion of the top wall within sight from the outside of the housing and toward the collection chamber, said transparent portion of the top wall having a baffle portion positioned in the horizontal path of the corn and directing it downwardly into the collection chamber, and means for dispensing the corn from the collection chamber. 35

7. A popcorn dispenser comprising a housing having a top wall with a transparent portion, a storage chamber in the housing for containing

5 popped corn to be dispensed, an overflow collection chamber adapted to contain a predetermined quantity of corn and to overflow downwardly any corn received in excess of said quantity, means for creating a flow of air upwardly in the housing, means for entraining corn from the storage chamber in said flow of air and discharging it upwardly and openly toward the top wall, said last mentioned means including a tube extending vertically within the storage chamber for passing the air and corn upwardly and having an upwardly opening upper discharge end, a baffle formed separately from said tube positioned in the upward path of the corn thus entrained and acting to direct it generally horizontally along the inside of the transparent portion of the top wall within sight from the outside of the housing and toward the collection chamber, said transparent portion of the top wall having a baffle portion positioned in the horizontal path of the corn and directing it downwardly into the collection chamber, and means for dispensing the corn from the collection chamber.
